US00D882644S

(12) **United States Design Patent** (10) **Patent No.:** **US D882,644 S**
(45) **Date of Patent:** **** Apr. 28, 2020**

(54) **BUCKET SHROUD**

(71) Applicant: **Caterpillar Inc.**, Deerfield, IL (US)

(72) Inventors: **Nathan Bjerke**, Peoria, IL (US);
Thomas Marshall Congdon, Dunlap, IL (US); **Samuel August Buckholz**, Dunlap, IL (US)

(73) Assignee: **Caterpillar Inc.**, Peoria, IL (US)

(**) Term: **15 Years**

(21) Appl. No.: **29/665,446**

(22) Filed: **Oct. 3, 2018**

(51) LOC (12) Cl. **15-03**

(52) U.S. Cl.

USPC **D15/29**; D15/28

(58) **Field of Classification Search**

(57) **CLAIM**

The ornamental design for a bucket shroud, as shown and described.

DESCRIPTION

FIG. 1 is a front perspective view of a bucket shroud showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate structure or features which form no part of the claimed design.

The drawings include surface shading which represents contour and not surface ornamentation.

1 Claim, 6 Drawing Sheets
